Primary Examiner—Ted Shooman*Assistant Examiner*—C. Tuttle*Attorney, Agent, or Firm*—John P. O'Banion**[57]****CLAIM**

The ornamental design for a ratchet link, as shown and described.

DESCRIPTION

FIG. 1 is a top front perspective view of a ratchet link showing our new design;

FIG. 2 is a left side elevational view thereof, the side opposite being a mirror image of the side shown;

FIG. 3 is a top plan view thereof;

FIG. 4 is a bottom plan view thereof;

FIG. 5 is a front elevational view thereof; and,

FIG. 6 is a rear elevational view thereof.
